(57) CLAIM

The ornamental design for a composition of twisted springs, as shown.

DESCRIPTION

FIG. 1 is a front elevational view of a composition of twisted springs, showing my new design,

FIG. 2 is a top plan view thereof;

FIG. 3 is a front elevational view of one element shown separately for clarity of illustration; and,

FIG. 4 is a front elevational view of one element shown separately for clarity of illustration.

The wires and supporting elements in all of the views form no part of the claimed design;
